US00D978375S

(12) **United States Design Patent** (10) **Patent No.:** **US D978,375 S**
(45) **Date of Patent:** **** Feb. 14, 2023**

(54) **REAGENT CONTAINER**

(71) Applicant: **Abbott Laboratories**, Abbott Park, IL (US)

(72) Inventor: **Robert Paul Luoma, II**, Colleyville, TX (US)

(73) Assignee: **Abbott Laboratories**, Abbott Park, IL (US)

(**) Term: **15 Years**

(21) Appl. No.: **29/745,034**

(22) Filed: **Aug. 3, 2020**

Related U.S. Application Data

(60) Division of application No. 29/721,476, filed on Jan. 21, 2020, now Pat. No. Des. 892,350, which is a division of application No. 29/640,810, filed on Mar. 16, 2018, now Pat. No. Des. 875,269, which is a division of application No. 29/531,426, filed on Jun. 25, 2015, now Pat. No. Des. 815,299, which is a continuation of application No. 13/801,154, filed on Mar. 13, 2013, now Pat. No. 9,535,082.

CLAIM

The ornamental design for a reagent container, as shown and described.

DESCRIPTION

FIG. 1 is a front right perspective view of a reagent container.

FIG. 2 is a front side view of the reagent container of FIG. 1; and,

FIG. 3 is a rear side view of the reagent container of FIG. 1. The broken lines in the drawings depict portions of the reagent container that form no part of the claimed design.

1 Claim, 3 Drawing Sheets
